UNITED STATES PATENT OFFICE.

THOMAS PHILLIPS, ELI BOUCHARD, AND TREFFLÉ CHARBONNEAU, OF WORCESTER, MASSACHUSETTS.

HORSESHOE.

SPECIFICATION forming part of Letters Patent No. 336,154, dated February 16, 1886.

Application filed January 6, 1886. Serial No. 187,756. (No model.)

To all whom it may concern:

Be it known that we, THOMAS PHILLIPS, ELI BOUCHARD, and TREFFLÉ CHARBONNEAU, all residents of the city and county of Worcester, State of Massachusetts, have invented 5 a new and useful Improved Horseshoe, of which the following is a specification.

Our invention belongs to that class of shoes having removable calks capable of being renewed without removing the shoe from the foot of the horse.

Its nature and principles of construction and operation are fully shown in the following description of the accompanying drawings, 15 which illustrate a shoe embodying our invention.

In said drawings, Figure 1 is a plan or view of the bottom of the shoe with the calks in place. Fig. 2 is a side or edge view, as indicated by 20 the arrow *b*, of one of the heels with its screw and calk removed; and Fig. 3 is a view of the front or toe calk, as indicated by the arrow *a*, with its screw removed and calk lifted.

The same letters indicate the same parts 25 wherever they occur.

A is the shoe; *B*, the toe-calk; *CC'*, the heel-calks; *e e e*, heads of bolts or screws holding the calks to the shoe.

At the toe of the shoe we make a recess as 30 long as it is desirable to have the toe-calk, cutting it about one-half the thickness of the shoe, as shown in Fig. 3, and leave a boss or thimble, *D*, long enough to reach nearly through the base of the toe-calk, and having a 35 threaded hole extending through it and the shoe, in which the bolt or screw is fitted to hold the calk in place. In this recess we also make two holes near its front and ends, as indicated by dotted lines in Figs. 1 and 3. The 40 calk, which may be of any of the common forms in use, has a base attached, fitted to fill

the above-described recess, and with a hole fitting the thimble *D*, and also two studs fitting the holes in the shoe, as shown in Fig. 3.

E is the screw or bolt, fitted to the thimble *D*, and having its head *e* large enough to bear on the base of the calk around the thimble. The heel-calks are similarly fitted in their recesses, excepting that one stud is deemed sufficient, as shown in Fig. 2, though two might 50 be used, and the toe-calk might be fitted with two thinbles and screws, if desirable, for large shoes.

The body of the shoe is made in any of the common forms designed to be fastened to the 55 horse's foot, the calks being removable by loosening their screws, so that long sharp calks can be easily put on for an icy time, and short or smoother ones for pavements or summer wear be easily substituted when desired.

The use of the thimble gives a long hold for 60 the screw, and its sides with the studs and ends of the recesses to which the base of the calk is well fitted all insure a firm solid union when the bolt is tightened.

Having thus fully described our invention, 65 what we claim as new, and desire to patent, is—

The removable-calk shoe described, having 70 its calks fitting in recesses, and provided with one or more studs fitting holes in the shoe, and an opening fitting over the thimble or nut on the shoe, with a bolt or screw holding them 75 firmly in place, all constructed and operating substantially as and for the purposes as above set forth.

THOMAS PHILLIPS.

ELI BOUCHARD.

TREFFLÉ CHARBONNEAU.
